(57) **CLAIM**

The ornamental design for a seat-top storage device as shown and described.

DESCRIPTION

FIG. 1 is a front perspective view of a seat-top storage device showing my design;

FIG. 2 is a front elevational view of the seat-top storage device of FIG. 1;

FIG. 3 is a rear elevational view of the seat-top storage device of FIG. 1;

FIG. 4 is a right-side elevational view of the seat-top storage device of FIG. 1;

FIG. 5 is a left-side elevational view of the seat-top storage device of FIG. 1;

FIG. 6 is a top plan view of the seat-top storage device of FIG. 1;

FIG. 7 is a bottom plan view of the seat-top storage device of FIG. 1;

FIG. 8 is a right front perspective view of the seat-top storage device of FIG. 1, shown employed with a vehicle seat;

FIG. 9 is a left front perspective view of the seat-top storage device of FIG. 1, shown employed with the vehicle seat; and,

FIG. 10 is a left front perspective view of the seat-top storage device of FIG. 1, shown employed with the vehicle seat in a mode of operation where the seat-top storage device contains an article.

The portions of the seat-top storage device shown in broken line do not form part of the claimed design.

The seat shown in broken lines in FIGS. 8, 9, and 10 is for environmental subject matter only and forms no part of the claimed design.

1 Claim, 8 Drawing Sheets
